UNITED STATES PATENT OFFICE.

GEORGE BENSON, OF BELFAST, IRELAND.

APPAREL-CUFF.

SPECIFICATION forming part of Letters Patent No. 402,223, dated April 30, 1889.

Application filed January 28, 1889. Serial No. 297,796. (No model.)

To all whom it may concern:

Be it known that I, GEORGE BENSON, of Belfast, Ireland, in the Kingdom of Great Britain, have invented a certain new and useful

5 Improvement in Cuffs, of which the following is a specification.

I will describe a cuff embodying my improvement in detail, and then point out the novel features in claims.

10 In the accompanying drawings, Figure 1 is a face view of a cuff embodying my improvement. Fig. 2 is a transverse section of the same, taken on the plane of the dotted line *x*, Fig. 1, and showing a portion of the wristband to which the cuff is attached. Fig. 3 is a detail showing a portion of a flap or apron comprised in the cuff, and Fig. 4 is a front view showing the cuff attached to a shirt-wristband.

15 20 Similar letters of reference designate corresponding parts in all the figures.

A designates the body of the cuff. The cuff is what is known as a "reversible cuff." I have shown button-holes *a* near its ends, 25 adapted to receive links or studs. These button-holes may, however, be omitted, and a tongue, *o*, be used provided with a button-hole, *f*, adapted to register with a button-hole, *g*, in the cuff, as shown in dotted outline in 30 Fig. 1.

B B' designate a flap or apron. This flap or apron is secured at its inner edge to the body of the cuff at about midway in the width of the latter, and is of nearly the same length 35 at its inner edge as the body of the cuff. It is attached to the outside face of the body of the cuff. The flap or apron comprises two end portions, *B*, and a central portion, *B'*, united at its ends to the portions *B*. I prefer that 40 the end portions, *B*, should be thicker than the portion *B'*—as, for instance, the end portions may be two or more ply, while the central portion may be but one ply. The outer edge of the flap or apron is free, so that the flap or 45 apron may be turned in either direction over against the face of the cuff. The outer edge of the central portion, *B'*, is longer than the inner edge thereof, so that the central portion is "full." This is accomplished by cutting the 50 central portion semicircular, as shown more clearly in Fig. 3. The end portions, *B*, act as

stiffeners for the flap. The central portion, *B'*, may likewise be provided with a stiffener, if desired. I have shown such an arrangement in dotted outline in Fig. 1.

55

As shown, the portions *B* of the flap or apron are provided with button-holes *c* near their lower edges, which will register or approximately register with the button-holes *a* in the body of the cuff when the flap or apron is 60 folded down. The button-holes *c*, when used, need not, however, register with the button-holes *a*, as the cuff may be attached to the wristband of a shirt by passing buttons through the button-holes *c* only and through 65 suitable button-holes in the wristband. It may also be secured by passing buttons through the button-holes *a* only and through the button-holes in the wristband. The flap or apron may have a button-hole, *d*, in the 70 central portion, *B'*, as shown in dotted outline in Fig. 1, if desirable.

In Figs. 2 and 4 I have shown the wristband of a shirt attached to the cuff. D designates the wristband. It extends between the flap 75 or apron *B B'* and the body of the cuff. In this case buttons *h* pass through both the button-holes *c a* to secure the cuff to the wristband.

The cuff effectually conceals the wristband 80 of the shirt. The portion *B'* of the flap or apron gives the cuff the appearance of being attached directly to a shirt-sleeve and not to a shirt-band. Of course when the cuff is reversed the flap or apron is to be reversed.

85

By making the portion *B'* of the flap thinner than the end portions, *B*, the said flap, when placed upon the wristband, not only causes the cuff to present the appearance of forming a part of the wristband, but it also provides 90 for the ready yielding or bending of the flap about the wristband. This latter function is facilitated by the method of cutting the central portion, *B'*, of the flap so that it is longer upon its outer edge than it is upon its inner 95 edge, as the flap may, when placed upon the wristband, be brought around and buttoned very easily, as shown more clearly in Fig. 4.

What I claim as my invention, and desire to secure by Letters Patent, is—

100

1. A reversible cuff having an attached flap or apron, said flap or apron being provided

with a thin flexible central portion and end portions thicker than said central portion, substantially as specified.

2. A reversible cuff having an attached flap or apron, said flap or apron being provided with a thin flexible central portion and end portions thicker than said central portion, the central portion being longer upon its outer edge than upon its inner edge, substantially as specified.

3. A reversible cuff having an attached flap or apron, said flap or apron being provided with a thin flexible central portion and end portions thicker than said central portion, said central portion being made in semicircular form, substantially as specified.

GEORGE BENSON.
